UNITED STATES PATENT OFFICE

STELLA MERTENS, OF PARIS, FRANCE

UNIT ELEMENT FOR THE PACKING OF FRUITS, EARLY PRODUCTS, FRAGILE OBJECTS,
AND THE LIKE, AND PROCESS OF MANUFACTURE OF THE SAME

Application filed October 12, 1928, Serial No. 312,161, and in France August 6, 1928.

The present invention has for its object a unit packing element adapted to receive and protect all objects and chiefly those which are extremely fragile or perishable, such as 5 fruits, early fruits or vegetables, glassware, or the like, characterized in that it consists of a series of contiguous recesses which are secured together and the deformable walls, whose thickness and nature of which are 10 suited to the packed object, conform to the latter and effectively protect it against the various dangers to which it is subjected.

The said element is further characterized in that it permits the simultaneous handling 15 of a number of objects without requiring the direct handling or contact of each object, which is of great importance in the case of fruits and the like.

The invention further relates to the manufacture of the aforesaid packing element 20 which consists in principle in forming, by means of bands of equal width and of suitable nature, thickness, and colour, and placed together in pairs, a composite folded device 25 of accordion or bellows characteristics; in straightening the object obtained by such folding, and in compressing it on its lateral ridges, so that it will assume the form of a series of cells or pockets which are flexible 30 and contiguous, and whose base is then closed by pasting, sewing or by like means.

The invention further relates, in addition to the use of all suitable substances for the manufacture of the packing element above 35 mentioned, to all combinations by juxtaposition, sewing, pasting, or the like, of such unit elements in any suitable number, so as to form single, double or multiple plates of various forms and dimensions, which are 40 compressible and extensible, and may be used for the packing of all products and for the filling of all cases, boxes, and display articles, due to the attractive display obtained by the new product according to the 45 invention.

A constructional form of the said product is specified in the following description with reference to the accompanying drawings.

Figure 1 is a plan view showing the initial 50 step in the formation of the packing unit.

Figures 2, 3, 4 and 5 are similar views showing successive steps in the development of the unit, the arrows *a*, *b*, *c*, *d* indicating the direction in which the successive folds are made. 55

Figure 6 shows the accordion formation obtained by the steps illustrated in Figures 2 to 5, the accordion-like element being unfolded. 60

Figure 7 shows the manner in which the cells of the accordion are straightened and their open sides brought into the same plane. 65

Figure 8 shows in perspective, the element resulting from the manipulation illustrated in the preceding figures. 65

Figures 9 and 10 show the element respectively in elevation and in plan.

Figure 11 is a view of a plate formed by a series of assembled cellular units.

Figure 12 represents a particular manner 70 of assembling units whereby double ends of the units may be used.

Figure 13 is a detail sectional view of a band or strip suitable for the formation of the units. 75

In carrying out the invention, two bands of flexible material suitable for cushioning the objects to be packed are secured firmly together at one end with the strips disposed at a right angle to each other and the ends overlapping, as seen in Figure 1, the extremities of the bands or strips being united by pasting, sewing, or otherwise. The strip 2 is next folded over across the strip 1 and the strip 1 then folded over across the strip 2, 80 these folds being repeated until the entire length of the strips has been folded in an accordion formation, as will be understood upon reference to Figures 2, 3, 4, 5 and 6. After the entire strips have been thus folded alternately one upon the other, a pull is exerted upon the ends of the unit thus produced, and the unit then presents a series of contiguous cells disposed helicoidally. The several cells are then submitted to lateral pressure upon their opposite ridges so that the tops 3 and 4 of each cell will be disposed in the same plane with the tops 5 and 6 and portions 7 and 8 will be lapped and extend obliquely relative to the medial lines of the 85 90 95 100

strips or bands, the action imparting a torsional movement of ninety degrees to each of the cells relative to the cell immediately preceding it, so that the resulting structure is a series of connected cells having four sides and four angles and opening all at one side of the strip or band. The cells are completed by fastening the edges of the interlaced strips along the bottom or that side of the unit opposite the open sides or tops of the cells. A series of such cells having a determined length will thus form a packing element 9 whose dimensions may be as desired for use for any particular purpose.

The invention further relates to all the combinations of unit elements as above specified, for the obtainment of composite devices, plates or the like (Fig. 11) formed by the juxtaposition of unit elements 9, these being joined by pasting or by like means.

The said units when joined together in pairs (Fig. 12) by means of a single or double seam, by pasting, or by like means, form a modified construction according to the invention, permitting the obtainment of a double unit element, and to set out a series of elements or plates whose lower face serves to cover the preceding, whilst the upper part serves as a receptacle and support for the fragile objects to be packed or exhibited.

The formation of the bands is covered by the invention. For this purpose, the single or multiple bands preferably comprise two paper walls 19 and 20, of a flexible and strong nature, between which is interposed a cushion 21 of suitable material for absorbing the shocks such as wadding, cotton, tow, or the like.

The bands 1 may also consist of braids or tresses of widely varying material adapted for different cases of packing, without departing from the principle of the invention, which chiefly relates to the use, in the aforesaid packing method, of the following substances: cotton in the form of yarn, cloth, braids, knitting goods, or the like, or wool, tow, flock, cellulose, wood fibre, paper fibre and the like, paper and pastboard, various pastes, wadding, kapok, peat fibre, stems and braids of textile or other fibres, fibres and straw of the cocoa or other plants, dried seaweed, or like material suitable for the manufacture of strong and soft bands which are adapted, after the manufacture of the said unit elements, to contain, protect and display the fragile or other goods which are to be packed and handled.

For this purpose, the bands and the material used in their manufacture may be coloured, worked, draped and treated in such manner as to be given an aspect suitable for each object or to each method of display desired, or the special qualities in view, and chiefly in the uses to be made of the said method, for the packing of fruits, early

fruits and the like, perishable or fragile goods, prepared food, cakes, biscuits, jellies, and the like, and in other classes, jewelry, watches, porcelain wares, glassware, electric lamps, instruments of precision, bottles of perfume or other liquids, pharmaceutical products and all objects of art or goldsmiths' work.

Due to its process of manufacture, the new product as above specified, will offer numerous advantages, and chiefly from the fact that the recesses of the unit packing elements are flexible and extensible, and will coincide with the form and to a certain degree with the dimensions of the object which they contain. They protect the said object by the thickness and the softness of their walls.

The multiple units thus obtained by juxtaposition will permit the handling without touching them, of all objects which might be damaged by contact, such as peaches, high class or luxury fruits, and these may be preserved for a long time in their original state of freshness. The bands may be given insulating or preserving qualities by a preliminary impregnation, which will fit them for the preservation of substances sensitive to heat or cold, pharmaceutical products, or the like.

Obviously, the aforesaid dispositions are given solely by way of example, and the forms, material, and dimensions of the constructional parts as well as the details may be modified without departing from the principal of the invention.

I claim:

1. The method of forming a packing element which consists in fastening two connected strips of materials at one end at a right angle to each other, folding the strips each upon the other alternately, stretching the folded strips longitudinally, and uniting the longitudinal edges of the strips at one side of the connected element.

2. The method of forming a packing element which consists in placing two flexible strips of equal size perpendicularly to each other, folding the strips alternately one across the other, stretching the folded strips longitudinally to produce a helicoidal series of contiguous cells, applying lateral pressure to the cells at opposite sides and simultaneously twisting the cells to bring their tops into one plane, and uniting the strips at the bottom of the cells.

3. A packing element consisting of two elongated interfolded strips forming a connected series of cells all opening along one side of the element, the component interfolded strips being fastened together along the opposite side of the element.

In testimony whereof I affix my signature.

STELLA MERTENS.
